UNITED STATES PATENT OFFICE

2,283,350

COMPOSITION FOR BLEACHING HAIR

Nathaniel Baum, Chicago, Ill., assignor to
McLaughlin & Wallenstein, Chicago, Ill.No Drawing. Application February 15, 1939,
Serial No. 256,453

8 Claims. (CL. 167—83)

My invention relates to the bleaching of hair, the term "hair" being used herein to mean hair on the human head.

In the bleaching of hair, it has long been the practice to employ a peroxide, specifically hydrogen peroxide. In view of the fact that hydrogen peroxide decomposes in an alkaline medium, the regular practice in bleaching the hair has been to admix aqueous hydrogen peroxide of desired volume strength with an aqueous solution of ammonia immediately prior to application to the hair, the ammonia acting to de-stabilize the hydrogen peroxide and accelerate the release of oxygen therefrom to effect the bleaching. The procedure described hereinabove, though practiced on a large scale prior to my present invention, possesses several serious disadvantages. In the first place, the bleaching treatment results in drying out of the hair and rendering it brittle. Indeed, this is so well recognized that it is commonly recommended that hair be not given a permanent wave until after the lapse of a week or more after it has been bleached so that the dryness and brittleness caused by the bleaching is to some extent overcome. Another objection to present practice, as outlined above, is the unpleasantness caused by the ammonia odor. A still further disadvantage is due to so-called overlapping. In other words, the compositions as employed tend to over-run on previously bleached hair, it being difficult to confine said compositions to the local areas desired to be bleached. Other objections are known to those skilled in the art which it is unnecessary at this time to consider.

I have discovered a novel method of bleaching hair and have evolved new and useful compositions therefor which overcome the various objections to and disadvantages of heretofore known practices. Thus, for example, the dryness and brittleness which characterize the condition of the hair after bleaching in accordance with prior procedure vanish when my process is practiced. The elasticity of the hair is preserved and permanent waving may be carried out immediately after bleaching and drying of the hair with no adverse effects. Furthermore, overlapping is obviated in a simple and effective manner. Additional advantages also result including remedying to a considerable extent the matter of objectionable ammoniacal odors which are so characteristic of prior art hair bleaching methods.

In general, the improved results of my invention are brought about by the utilization of an

oleaginous solution of an amine, preferably in the presence of supplementary agents, as hereinafter set forth in detail. This oleaginous solution is mixed with an aqueous solution of a peroxide, particularly hydrogen peroxide, and the resulting emulsion or dispersion is applied to the hair relatively promptly or shortly thereafter. After the bleaching has been completed, the composition is readily washed from the hair.

10 The oleaginous material may be of fixed or volatile character and may be selected from the group consisting of animal, vegetable and mineral oils. Because of considerations of substantial freedom from the tendency to oxidize and 15 thereby become rancid or otherwise produce undesirable flavors and odors, I prefer to employ mineral oils, preferably water-white and of a consistency generally similar to those of the medicinal variety. I may, however, employ animal and vegetable or triglyceride oils such as refined lard oil, refined peanut oil, refined cottonseed oil, and the like.

15 The amines which I employ are soluble or dispersible in the oleaginous medium or media 20 which are utilized. They are preferably also soluble or dispersible in aqueous media. They may be of aliphatic, araliphatic, aromatic or hydroaromatic character and should, of course, be of a type which will not be acted upon by peroxides or particularly hydrogen peroxide to form colored or undesired colored reaction products. 25 Because of matters of innocuousness and for other reasons, I prefer to employ aliphatic amines and particularly the hydroxylalkyl amines 30 or alkylolamines. Among such compounds may be mentioned, for example, monoethanolamine, diethanolamine, triethanolamine and mixtures thereof including such as occur in commercial triethanolamine, morpholine, propanolamines including normal propanolamine and tri-isopropanolamine, butanolamines, pentanolamines, hexanolamines, glycerolamines; alkylol polyamines such as alkylol derivatives of ethylene diamine and diethylene tetramine; alkylated and 35 other derivatives of the alkylolamines including, for example, diethylaminoethanol, phenyl ethanolamine, phenyl diethanolamine, cyclohexyl ethanolamine, phenyl morpholine, monomethyl ethanolamine, dimethyl ethanolamine, monoethyl triethanolamine, diethyl triethanolamine, ethyl phenyl ethanolamine, and the like; alkyl amines such as ethylene diamine, diethylene triamine, triethylene tetramine, butyl amine, hexyl amine, octyl amine, lauryl amine, mono-methyl ethylene diamine, mono-ethyl diethylene tri-

40 including normal propanolamine and tri-isopropanolamine, butanolamines, pentanolamines, hexanolamines, glycerolamines; alkylol polyamines such as alkylol derivatives of ethylene diamine and diethylene tetramine; alkylated and other derivatives of the alkylolamines including, for example, diethylaminoethanol, phenyl ethanolamine, phenyl diethanolamine, cyclohexyl ethanolamine, phenyl morpholine, monomethyl ethanolamine, dimethyl ethanolamine, monoethyl triethanolamine, diethyl triethanolamine, ethyl phenyl ethanolamine, and the like; alkyl amines such as ethylene diamine, diethylene triamine, triethylene tetramine, butyl amine, hexyl amine, octyl amine, lauryl amine, mono-methyl ethylene diamine, mono-ethyl diethylene tri-

amine, 1,1-dimethyl ethylene diamine, and the like; and aromatic and heterocyclic bases such as pyridine, benzyl amine and homologues and derivatives or substitution products thereof.

I have also found it to be highly desirable, although not essential so far as the broader aspects of the invention are concerned, to utilize, in the oleaginous solution of the amine, a proportion of an emulsifying agent which is soluble or dispersible in the oleaginous solution of the amine. While various emulsifying agents may be utilized, I have obtained unusually satisfactory results by employing salts or soaps of the amines with higher molecular weight carboxylic or fatty acids such as monoethanolamine oleate, tri-¹⁵ ethanolamine oleate, diethanolamine laurate, ethylene diamine laurate and the like. Among the higher molecular weight carboxylic or fatty acids whose salts with any one or more of the amines mentioned hereinabove may be employed for the present purpose are the straight chain and branched chain, saturated and unsaturated, acids including, by way of example, caproic acid,

capric acid, sebacic acid, cerotic acid, erucic acid, melissic acid, stearic acid, oleic acid, ricinoleic acid, linoleic acid, linolenic acid, lauric acid, myristic acid, palmitic acid, mixed higher fatty acids derived from animal or vegetable sources such as lard, coconut oil, sesame oil, palm oil, olive oil, peanut oil, soya bean oil, coconut oil, castor oil, seal, whale and fish oils and the like. Such acids may contain substituent groups such as hydroxy, halogen, ketone, amide, carbonyl, amine and other groups. Of especial utility is oleic acid and particularly in the form of monoethanolamine oleate, diethanolamine oleate or triethanolamine oleate.

I have discovered, furthermore, that the improvements which are brought about in accordance with my invention as described are still further enhanced if there is included in the oleaginous solution of the amine and emulsifying agent a higher molecular weight alcohol. The higher molecular weight alcohol serves several functions. It tends to produce a product having a thicker consistency which serves to prevent overlapping on previously bleached hair. It also functions to enhance the wetting action of the oleaginous material with respect to the hair and, in addition, it serves in the role of a solubilizing agent for the composition. Thus, when a solution is made up containing, for example, mineral oil, oleic acid, and monethanolamine substantially in excess of that required to neutralize the oleic acid, the resulting solution is not clear. The addition of a suitable proportion of a higher molecular weight alcohol, such as lauryl alcohol, serves to render the solution clear or transparent. In general, while the proportion of such alcohol is variable, a satisfactory range is from about 10% to about 20% of the composition. Among the higher molecular weight alcohols which may be utilized may be mentioned, for example, octyl alcohol, nonyl alcohol, decyl alcohol, undecyl alcohol, linoleyl alcohol, stearyl alcohol, ricinoleyl alcohol, palmitoleyl alcohol, lauryl alcohol, myristyl alcohol, cetyl alcohol, oleyl alcohol, melissyl alcohol, ceryl alcohol, carnaubyl alcohol, myricyl alcohol, higher molecular weight glycols such as cetene glycols and other vicinal glycols, branched chain octyl, decyl, dodecyl, tetra-decyl and octa-decyl aliphatic alcohols, as, for example, 2-n butyloctanol-1, 2-butyl tetra decanol-1, and, in general, the higher molecular weight saturated and unsaturated aliphatic straight chain and

branched chain alcohols. Preferably the alcohols which are utilized are those corresponding to the fatty acids occurring in triglyceride oils and fats of vegetable and animal origin, natural or hydrogenated, such as corn oil, cottonseed oil, sesame oil, coconut oil, palm kernel oil, lard, soya bean oil, and the like, those alcohols containing from 12 to 18 carbon atoms being preferred. I have obtained especially satisfactory results with coconut oil mixed fatty alcohols containing a predominant proportion of lauryl alcohol.

In order that the full significance of the invention may be made more apparent, the following illustrative examples are set forth. It will be appreciated that the proportions of the ingredients may be varied, different combinations thereof may be employed and other changes may be made in the light of the guiding principles disclosed hereinabove. The examples are, therefore, to be construed in an illustrative and not in a limiting sense. All parts given in the examples are by volume.

Example 1

	Parts
25 Mineral oil	50
Oleic acid	30
Monoethanolamine	20
Lauryl alcohol	20

Example II

		Parts
30	Refined peanut oil	60
	Lauric acid	40
	Ethylene diamine	18
35	Oleyl alcohol	10

Example III

	Parts
Mineral oil	50
Oleic acid	30
40 Monoethanolamine	14
Morpholine	10
Lauryl alcohol	10

Example IV

45	Part
Mineral oil	6
Oleic acid	3
Monoethanolamine	2

50 In use, immediately or shortly prior to the application to the hair, the oleaginous compositions described hereinabove are mixed with aqueous hydrogen peroxide. Thus, for example, one part by volume of the oleaginous preparation may be mixed with from 2 to 5 parts by volume of hydrogen peroxide of 17 to 20 volume strength. A uniform, oleaginous emulsion is produced which is then applied to the hair. The proportions of the oleaginous preparation and the aqueous hydrogen peroxide employed may be varied, depending upon the rapidity of bleaching and the shade desired.

It will be understood, of course, that in all cases there is a sufficient content of free amine in the oleaginous solution so that when the latter is mixed with the aqueous hydrogen peroxide or the like the resulting emulsion or dispersion is alkaline in reaction.

As indicated hereinabove, the proportions of the various ingredients are subject to considerable variation. Thus, for example, the oleaginous material may range from 40 to 60 parts by volume, the amine from 10 to 25 parts by volume, the emulsifying agent, when used, 0.5 to 50 parts or more, and the higher molecular weight alcohol,

when used, from about 10 to about 20 parts by volume.

Supplemental agents such as perfume and the like may, of course, be added to the composition without in any manner departing from the spirit of the invention as set forth in the appended claims.

Wherever the term "higher" is used hereinabove and in the claims, as applied to fatty acids, alcohols and the like, it will be understood to mean at least 8 carbon atoms unless otherwise specifically stated.

What I claim as new and desire to protect by Letters Patent of the United States is:

1. A liquid composition for use with an aqueous solution of a peroxide for the bleaching of hair comprising an oleaginous solution of an aliphatic amine and an emulsifying agent.

2. A liquid composition for use with an aqueous solution of a peroxide for the bleaching of hair comprising an oleaginous solution of an aliphatic amine and an alkylolamine soap.

3. A liquid composition in accordance with claim 2 wherein the ingredients are present in substantially the following proportions:

	Parts
Oleaginous material	40 to 60
Aliphatic amine	10 to 25
Emulsifying agent	0.5 to 50

4. A liquid composition for use with an aqueous solution of a peroxide for the bleaching of hair comprising an oleaginous solution of an ali-

2,283,350

phatic amine, an alkylolamine soap, and a higher molecular weight alcohol.

5. A liquid composition for use with an aqueous solution of a peroxide for the bleaching of hair comprising an oleaginous solution of an aliphatic amine, an emulsifying agent, and an aliphatic alcohol containing from eight to eighteen carbon atoms.

6. A liquid composition for use with an aqueous solution of hydrogen peroxide for the bleaching of hair comprising mineral oil, an aliphatic amine, a salt of an aliphatic amine and a higher fatty acid, and a higher molecular weight alcohol.

7. A liquid composition for use with an aqueous solution of hydrogen peroxide for the bleaching of hair comprising the following ingredients in the stated proportions by volume:

	Parts
Oleaginous material	40 to 60
Amine	10 to 25
Emulsifying agent	0.5 to 50
Higher molecular weight aliphatic alcohol	10 to 20

8. A liquid composition for use with an aqueous solution of a peroxide for the bleaching of hair comprising a mineral oil solution containing an aliphatic amine, an alkylolamine soap, and a higher molecular weight alcohol containing at least a substantial proportion of lauryl alcohol.

NATHANIEL BAUM.
